UNITED STATES PATENT OFFICE.

TYSON THADDEUS FERREE, OF ASHBORO, NORTH CAROLINA.

INDICATOR.

Application filed December 26, 1923. Serial No. 682,751.

To all whom it may concern:

Be it known that I, TYSON THADDEUS FERREE, a citizen of the United States, residing at Ashboro, in the county of Randolph and 5 State of North Carolina, have invented a new and useful Indicator, of which the following is a specification.

This invention relates to an indicator designed primarily for signaling to persons outside of a building, the amount of merchandise to be delivered, it being possible to change the indicator by manipulating operating means located within the building on which the indicator is located.

The invention is adapted especially for use in indicating the amount of ice to be delivered to a building and has combined with it a means whereby a person within the building can readily determine by glancing 20 at the adjacent portion of the apparatus, exactly what information is displayed by that portion of the apparatus located outside of the building.

A further object is to provide simple and 25 efficient means for actuating the indicator and for maintaining it in any position to which it may be moved.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed may be made within the scope of what is claimed without departing from the spirit of the invention.

In the accompanying drawings the preferred form of the invention has been shown.

40 Figure 1 is a section through a portion of a building showing the apparatus applied thereto.

Fig. 2 is a front elevation of the exterior portion of the apparatus, a part of the housing being broken away.

Fig. 3 is a rear elevation of the structure shown in Fig. 2.

Fig. 4 is a section on line 4-4, Fig. 3.

Fig. 5 is an elevation of the operating 50 portion of the indicator.

Fig. 6 is a view partly in plan and partly in section of the structure shown in Fig. 5.

Referring to the figures by characters of reference, 1 designates a substantially circular housing having attaching means, such as ears 2, whereby it can be connected readily

to the outer wall W of a residence, or other structure indicated at S. Mounted within the housing 1 is a cross strip 3 and mounted for rotation in this cross strip and in the front of the housing is a shaft 4 to which is secured a grooved wheel 5. A disk 6 is also secured to and rotates with the shaft and is supported close to the front wall of the housing 1. A segmental opening 7 is formed in this front wall so that the disk 6 is exposed therethrough. The front face of the disk is divided by radial lines 8 into segmental portions and on each segmental portion is printed or otherwise displayed suitable data for the information of a dealer. For example, one space may contain the data "Ice 10" meaning ten pounds of ice. The next space can contain the data "Ice 25" meaning twenty-five pounds of ice. Thus the data in all the spaces will differ and one of the spaces, which is normally exposed through the opening 7 is left blank as shown. A spring 9 is mounted on the shaft and one end thereof is secured to the shaft while the other end is secured to the strip 3. This spring serves to hold the disk normally in one extreme position with the blank space thereof exposed in the opening 7. A projection 10 is provided on the housing and is normally engaged by a lug 11 on the disk so as to hold it in said extreme position.

Strip 3 has a guide ear 12 extending therefrom and movable within this ear is an operating wire or cord 13, one end portion of which is wrapped about the wheel 5 and secured thereto. This flexible operating element 13 engages suitably disposed guide pulleys 14 and is attached at a point within the structure S to one end of a rack bar 15 slidable within guides 16 that are secured to a plate 17. This plate is adapted to be fastened to a wall or the like within the structure S as shown in Fig. 1 and journaled within the plate 17 and within a cross strip 18 fastened to the end portions of the plate is a shaft 19 on which is secured a gear 20. This gear meshes with a rack 15 and by means of a detachable crank 21 the gear 19 and gear 20 can be rotated so as to move the rack 15 upwardly or longitudinally so as to pull on the connection 13. Gear 20 is held normally against rotation by a locking lever 22 and a spring 24 engages this lever and serves to hold it normally in contact with one of the teeth of the gear to prevent rotation thereof. A releasing handle 23 is

connected to the lever and is normally supported above the plate 17 as shown in Fig. 5.

A graduated strip 24 is extended from the plate 17 and a pointer or index 25 projects from the rack 15 and is designed to cooperate with the graduations 26 on the strip 24 to indicate to the user of the apparatus which item is displayed within the opening 7 of housing 1.

Under normal conditions the pointer 25 is located at the "0" graduation on the strip 24 and the blank space on disk 6 is displayed through the opening 7.

When it is desired to display, for example, the item "Ice 75," meaning seventy-five pounds of ice, the user of the apparatus rotates gear 20 so as to bring the pointer 25 to the graduation 26 indicated by the numeral 75. Connection 13 will thus rotate the wheel 5 against the action of spring 9 until the item "Ice 75" is displayed within the opening 7. Lever 22 will hold the rack 15 against return movement. After the ice has been delivered the user can disengage lever 22 from the gear 20 whereupon the spring 9 will reset all of the parts.

While this apparatus is designed primarily for use in notifying ice dealers as to the amount of ice desired, it can obviously be used for other purposes.

What is claimed is:—

1. In apparatus of the class described the combination with a rotatable indicator and flexible means connected thereto for actuating

the same, of a rack attached to said flexible means, yielding means for holding the indicator and the rack normally in one position, a graduated member adjacent the rack, means on the rack and cooperating with the graduated member for designating positions of the indicator connected to the rack, a gear for rotating the rack, and means detachably engaging the gear for holding the gear and rack against movement.

2. In a device of the class described the combination with a wall plate having a graduated strip constituting an extension thereof, of a rack slidably mounted on the plate, means carried by the rack and readable in connection with the graduations for indicating positions of an operated element, an indicator yieldingly held against movement, a flexible connection between the indicator and the rack, a gear meshing with the rack and journaled in the plate, means for rotating the gear, means for engaging the gear for holding said gear and the rack against movement, and a releasing handle connected to said means and supported beyond the plate.

In testimony that I claim the foregoing as my own, I have hereto affixed my signature in the presence of two witnesses.

TYSON THADDEUS FERREE.
